APPARATUS FOR DRYING OR MIXING
STONE OR THE LIKEBenson George Willis Bartlett, Darlington,
EnglandApplication July 22, 1932, Serial No. 624,064
In Great Britain July 25, 1931

8 Claims. (Cl. 308—203)

This invention relates to means for drying or mixing stone or the like of the type wherein the stone is mixed in a rotating drum or container, drying agents being passed through the drum for the purpose of drying the stone, the object being to provide improvements therein.

Apparatus made according to this invention comprises a drum adapted for rotation, a bearing ring fixedly secured to said drum and adapted to rotate therewith, a second bearing concentric with the first and in fixed relation with the supporting surface for the apparatus, and a plurality of members adapted for free rotation and located between the two bearing surfaces, and having their pivotal supports independent of either bearing members.

Referring to the accompanying drawing:—

Fig. 1 is a longitudinal part sectional elevation of one form of apparatus constructed in accordance with this invention; and

Fig. 2 is a corresponding end elevation.

Fig. 3 is a fragmentary longitudinal sectional elevation of a modified form of apparatus; and

Fig. 4 is a corresponding end elevation.

In Figs. 1 and 2, the drum *a* is provided with two or more tyres or series of tyres *b* rigidly secured thereto. Wood or metal chocks *c* are disposed between the drum and the tyres. The tyres are provided with external circumferential ribs *d*.

Two or more circular bearing members *e* are provided, rigidly mounted on supports *f*. Rails *g* are rigidly mounted within the bearing members *e*, and are provided with internal circumferential ribs *h*. The number and axial spacing of the rails *g* corresponds to the number and axial spacing of the tyres *b*.

The drum *a* is mounted within the bearing members *e*, each tyre *b* being in transverse alignment with a rail *g*, and a series of three or more flanged wheels or rollers *i* is disposed between each tyre *b* and the complementary rail *g* so that said rollers may be engaged by the ribs *d* on the tyres *b* and the ribs *h* on the rails *g*. The rollers *i* in each series are disposed in spaced circumferential relationship about the drum *a*, and retained in such relative positions by a tie ring *j* which provides bearings for the free rotation of the spindles *k* of the rollers.

The tyres *b* are disposed, as illustrated, in series of two, and each bearing member *e* is provided with two rails *g*, or one rail with two ribs *h*. A series of rollers or wheels *i* may be provided, as illustrated, for each tyre *b* and rail *g*.

The rollers of one series are in axial alignment

with the rollers of the adjacent series and have a common spindle, as illustrated.

A grooved or flanged ring *m* is also rigidly secured to the drum *a*, chocks *n* being disposed therebetween, and a resilient ring or lining *o*, of leather, rubber, or other suitable material, is disposed in the groove *p*. A driving sprocket, gear wheel, or pulley may be mounted on the lining *o*, or a chain, belt, or the like may engage said lining so that a rotating drive may be transmitted to the drum *a*.

In operation, when the drum is caused to rotate, the tyres *b* roll on the rollers *i* which in turn roll on the rails *g*. In effect, the tyres *b* form the inner races, and the rails *g* the outer races of roller bearings.

In the modified form of apparatus illustrated in Figs. 3 and 4, a hollow boss or trunnion *q* is secured to each end of the drum *a* in axial alignment therewith. A tyre or inner race *b* is rigidly mounted externally on each boss *q*. Bearing members *e* are provided at each end of the drum, supported on members *f*. Linings or outer races *r* are mounted within the bearing members *e*. A series of three or more rollers *i*, in spaced relationship, are disposed between the races *b*, *r*, and adapted to engage therewith. The spaced relationship of the rollers *i* is retained by members *s* in the form of links pivoted to each other at, and providing bearings for, the roller spindles *k*.

Two series of roller *i* are provided in each bearing, as shown.

The races *b* and *r* are provided with ribs *d* and *h* which engage grooves *t* in the rollers *i*.

The roller spacing members *s* may be formed by discs providing bearings for the roller spindles *k* and also acting as shields to close in the ends of the bearings, central holes being provided to co-operate with the hollow centres of the bosses *q*.

The members *s* will travel round the bearing members *e* with the rollers *i*.

The drum *a* is rotated by any suitable means such as bevel or spur gearing, chain and chain sprocket, belt and pulley, or the like.

What I claim and desire to secure by Letters Patent is:—

1. Apparatus for drying or mixing stone or the like comprising a drum adapted for rotation, a plurality of bearing members fixedly secured to said drum and adapted to rotate therewith and each provided with two transversely spaced external circumferential ribs, a second series of bearing members concentric with the first and in fixed relation with the supporting surface for the

105

- apparatus, and each provided with two transversely spaced internal circumferential ribs, and a plurality of series of rolling members adapted for free and independent rotation on the bearing members and having their pivotal supports independent of the bearing members, each rolling member comprising two rollers axially connected and spaced, a bearing member of each series and a series of rolling members being arranged in a series, each roller being located between and rolling on a rib on each bearing member in the series. 5 80
2. Apparatus for drying or mixing stone or the like as claimed in claim 1 wherein bosses or trunnions are rigidly secured to each end of the drum and directly associated with the bearing members fixed to the drum. 10 85
3. Apparatus for drying or mixing stone or the like comprising a drum adapted for rotation, a plurality of bearing members fixedly secured to said drum and adapted to rotate therewith and each provided with two transversely spaced external circumferential ribs, a second series of bearing members concentric with the first and in fixed relation with the supporting surface of the apparatus, and each provided with two transversely spaced internal circumferential ribs, and a plurality of series of rolling members adapted for free and independent rotation on the bearing members and having their pivotal supports independent of the bearing members, each rolling member comprising two rollers axially connected and spaced, a bearing member of each series and a series of rolling members being arranged in a series, each roller being located between and rolling on a rib on each bearing member in the series, the bearing members on the drum being secured thereto by chocks driven between the external surface of the drum and the internal surfaces of the bearing members. 20 90
4. Apparatus for drying or mixing stone or the like comprising a drum adapted for rotation, a plurality of bearing members fixedly secured to said drum and adapted to rotate therewith and each provided with two transversely spaced external circumferential ribs, a second series of bearing members concentric with the first and in fixed relation with the supporting surface of the apparatus and each provided with two transversely spaced internal circumferential ribs, and a plurality of series of rolling members adapted for free and independent rotation on the bearing members and having their pivotal supports independent of the bearing members, each rolling member comprising two rollers axially connected and spaced, a bearing member of each series and a series of rolling members being arranged in a series, each roller being located between and rolling on a rib on each bearing member in the series, the bearing members on the drum being secured thereto by chocks driven between the external surface of the drum and the internal surfaces of the bearing members. 30 100
5. Apparatus for drying or mixing stone or the like comprising a drum adapted for rotation, a plurality of bearing members fixedly secured to said drum and adapted to rotate therewith and each provided with two transversely spaced external circumferential ribs, a second series of bearing members concentric with the first and in fixed relation with the supporting surface of the apparatus and each provided with two transversely spaced internal circumferential ribs, and a plurality of series of rolling members adapted for free and independent rotation on the bearing members and having their pivotal supports, independent of the bearing members, each rolling member comprising two rollers axially connected and spaced, a bearing member of each series and a series of rolling members being arranged in a series, each roller being located between and rolling on a rib on each bearing member in the series, means being associated with the bearing and rotary members to prevent longitudinal displacement of the drum. 40 105
6. Apparatus for drying or mixing stone or the like comprising a drum adapted for rotation, a plurality of bearing members fixedly secured to said drum and adapted to rotate therewith and each provided with two transversely spaced external circumferential ribs, a second series of bearing members concentric with the first and in fixed relation with the supporting surface of the apparatus and each provided with two transversely spaced internal circumferential ribs, and a plurality of series of rolling members adapted for free and independent rotation on the bearing members and having their pivotal supports, independent of the bearing members, each rolling member comprising two rollers axially connected and spaced, a bearing member of each series and a series of rolling members being arranged in a series, each roller being located between and rolling on a rib on each bearing member in the series, 50 110
7. Apparatus for drying or mixing stone or the like comprising a drum adapted for rotation, a plurality of bearing members fixedly secured to said drum and adapted to rotate therewith and each provided with two transversely spaced external circumferential ribs, a second series of bearing members concentric with the first and in fixed relation with the supporting surface of the apparatus and each provided with two transversely spaced internal circumferential ribs, and a plurality of series of rolling members adapted for free and independent rotation on the bearing members and having their pivotal supports independent of the bearing members, each rolling member comprising two rollers axially connected and spaced, a bearing member of each series and a series of rolling members being arranged in a series, each roller being located between and rolling on a rib on each bearing member in the series, the drum being furnished with a grooved driving ring encircling the drum and fixedly attached thereto and provided with a resilient lining. 60 115
8. Apparatus for drying or mixing stone or the like as claimed in claim 7 the driving ring being secured to the drum by chocks driven between the external surface of the drum and the internal surface of the driving ring. 65 120
